UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed December 30, 1929. Serial No. 417,329.

This invention relates to improvements in mining machines and more particularly has reference to improved flexible feeding means for a coal mining machine of the continuous cutter, bottom cutting type.

An object of this invention is to provide an improved coal mining machine. Another object is to provide an improved coal mining machine of the flexibly fed, bottom cutting type. A further object is to provide an improved feeding mechanism for a coal mining machine. Another object of this invention is to provide an improved coal mining machine of the flexibly fed, continuous cutter, bottom cutting type having improved feeding and guiding mechanism and more particularly improved feeding and guiding mechanism for a room and pillar type coal mining machine. Yet another object is to provide an improved bottom cutting mining machine of the room and pillar type having improved feeding and guiding mechanism wherein separate relatively rotatable feed operating and controlling members cooperating with separate flexible feeding elements are employed for feeding and guiding the machine. Another object is to provide in a flexible feeding means of the aforesaid character, improved driving and controlling means for the feed operating members whereby the latter may be separately or simultaneously driven in a direction to draw in their respective flexible feeding elements at relatively low speed or at relatively high speed. A further object is to provide in such a feeding means, improved mechanism whereby the feed operating members may rotate in a direction to pay out their respective flexible feeding elements under various degrees of operator-controlled frictional resistance or without such resistance, as conditions may require. Still another object is to provide in such a feeding means improved mechanism including a frictionally controlled fast speed gear train and a frictionally controlled slow speed gear train, and means for connecting either of said members to either train whereby said members may be rotated independently in winding direction at either a relatively high speed or a relatively low speed,

the said gear trains being common to the drive of both members. These and other objects and advantages of this invention will, however, subsequently more fully appear.

In the accompanying drawings there is shown for purposes of illustration, one embodiment which the invention may assume in practice.

In these drawings,

Fig. 1 is a plan view of a coal mining machine having embodied therein the illustrative form of the improved flexible feeding means.

Fig. 2 is a side elevational view of the machine shown in Fig. 1.

Fig. 3 is an enlarged horizontal sectional view taken substantially on line 3-3 of Fig. 2.

Fig. 4 is a longitudinally extending vertical sectional view taken substantially on line 4-4 of Figs. 1 and 3.

Fig. 5 is a longitudinally extending vertical sectional view taken substantially on line 5-5 of Fig. 3.

Fig. 6 is a detailed view, parts being shown in section, illustrating the controlling mechanism for the feed clutches.

Fig. 7 is a detail sectional view taken substantially on line 7-7 of Fig. 6.

In this illustrative construction there is shown a coal mining machine of the flexibly fed, room and pillar, bottom cutting type, although it is within the scope of this invention to apply the various novel features of the invention in coal mining machines of various other types. This mining machine generally comprises a low compact machine frame 1 of generally rectangular shape having a plane bottom surface 2 upon which the machine is slidably supported for movement over the mine bottom. As is usual in mining machines of the room and pillar type, rigidly secured within the machine frame and projecting forwardly lengthwise therefrom is an elongated plane cutter bar 3 supporting on its outer edges an endless cutter chain 4 having usual staggered cutter bits 5. Arranged at opposite sides of the machine frame at the rear end of the machine are relatively rotatable feed operating and controlling mem-

bers 6 and 7, herein in the form of cable winding drums, with which feeding and controlling cables 8 and 9 respectively cooperate. Carried by the machine frame is a motor 10 which may be of the reversible electric type having a power shaft 11 horizontally disposed and extending longitudinally of the machine. The cutter chain 4 is operatively connected to the forward end of the motor shaft through suitable transmission means which may be of the same general character as that disclosed in my copending application Ser. No. 179,357, filed March 29, 1927, patented July 21, 1931, Patent No. 1,815,873. The feed operating and controlling members 6 and 7 are operatively connected to the rear end of the motor shaft through improved transmission means to be hereinafter described. Arranged at the opposite rear corners of the machine frame on upstanding axes are guide sheaves 12, 13, 14 and 15, the guide sheaves 14 and 15 being horizontally swingable into different positions, while arranged at the opposite sides of the front end of the machine frame are vertically swingable swing arms supporting guide sheaves 16 and 17. The feed and controlling cables 8 and 9 after passing around any preferred guide sheaves may be extended in any preferred direction from the machine and attached to suitably positioned anchors in the manner which is well understood in the mining machine art.

Now referring to the improved feeding mechanism, and more particularly to the improved transmission means, it will be noted that secured to the rear end of the motor shaft 11 as shown in Fig. 4 is a spur pinion 18 meshing with an internal gear 19 secured to a horizontal longitudinally extending shaft 20 suitably journaled within the machine frame and having fixed thereto a bevel pinion 21 meshing with a bevel gear 22 secured to a vertical shaft 23. This shaft is suitably journaled within the machine frame and has fixed thereto intermediate its ends, a worm 24 meshing with a fast speed worm wheel 25 rotatably supported on a horizontal shaft 26 extending transversely of and suitably journaled within the machine frame. Suitably secured to the worm wheel 25 at opposite sides thereof are clutch housings 27 and 28 carrying the outer discs of multiple disc clutches 29 and 30 respectively. The inner discs of these clutches are carried by hollow shafts or sleeves 31 and 32 respectively, rotatably supported on the shaft 26 at opposite sides of the worm wheel 25. Carried by the sleeve 31 is a spur pinion 33 meshing with a spur gear 34 fixed to a transverse horizontal shaft 35 arranged parallel with and in front of the shaft 26 and likewise suitably journaled within the machine frame. Fixed to the shaft 35 is a spur pinion 36 meshing with an internal gear 37 carried by the wind-

ing drum 7. In the same manner the sleeve 32 carries a spur pinion 38 meshing with a spur gear 39 fixed to a transverse horizontal shaft 40, alined with the shaft 35 above referred to, and arranged at the opposite side of the machine. Secured to the shaft 40 is a spur pinion 41 meshing with an internal gear 42 carried by the winding drum 6. It will thus be seen that upon application of the friction clutch 29 the winding drum 7 may be driven from the motor in winding direction at a relatively high speed through the gearing 18, 19, 21, 22, vertical shaft 23, worm gearing 24, 25, shaft 31, spur gearing 33, 34, shaft 35 and spur pinion 36 meshing with internal gear 37 carried by the drum. It will also be noted that when friction clutch 30 is applied, the winding drum 6 may be driven from the motor in winding direction at a similar speed through a similar gear train, the gear train including gearing 18, 19, 21, 22, 23, 24, 25, being common to the drive of both the winding drums to effect rotation thereof through their respective reduction gearings either separately or simultaneously in winding direction at a relatively high speed. The operating means for the friction clutches 29, 30 will be hereinafter described.

The transmission means for effecting rotation of the winding drums in winding direction at relatively low speed includes a spur gear 43 (see Fig. 4) formed integral with the bevel gear 22 and likewise secured to the vertical shaft 23 and driving through idler gears 44 and 45, journaled on upstanding studs 46 carried by the bottom of the machine frame, a spur gear 47. As shown in Fig. 5, the spur gear 47 is fixed to the lower end of a vertical shaft 48 suitably journaled within the machine frame and having fixed thereto intermediate its ends, a worm 49 meshing with a slow speed worm wheel 50. The hub of this worm wheel, as shown in Fig. 3, is fixed to the transverse shaft 26 and is connectible by a multiple disc clutch 51 to the sleeve 32. In the illustrative construction shown, secured to the opposite end of the shaft 26 is a clutch housing 52 carrying the outer discs of a multiple disc clutch 53, the inner discs of this clutch being carried by the sleeve 31. It will thus be seen that when the clutch 29 is released and the clutch 53 applied, the winding drum 7 may be driven from the motor in winding direction at relatively low speed through gearing 18, 19, 21, 22, 43, 44, 45, 47, worm gearing 49, 50, transverse shaft 26, sleeve 31, spur gearing 33, 34, and the spur pinion 36 meshing with the internal gear 37 carried by the winding drum 7. It will also be noted that when the friction clutch 30 is released and the clutch 51 applied, the winding drum 6 may be driven from the motor at a similar speed in a similar direction through gearing 18, 19, 21, 22, 43, 44, 45, 47, worm gearing 49, 50, sleeve 32, spur gearing 130

38, 39 and spur pinion 41 meshing with the internal gear 42 carried by the winding drum 6. It will be noted that the slow speed gear train 18, 19, 21, 22, 43, 44, 45, 47, 48 and 50 is common to the drive of both the winding drums. It will also be seen that the friction clutches may be sufficiently released to permit the cable to unwind from the drums under various degrees of frictional resistance 10 under the control of the clutch operating mechanism. Upon release of the friction clutches the drums may be entirely relieved from any frictional resistance due to the action of the friction clutches. The operating mechanism for the clutches 51 and 53 will be later described. It will be observed that the winding drums 6 and 7 are arranged on horizontal axes extending transversely of and at opposite sides of the machine and each drum 20 is journaled on a laterally projecting stub shaft 54 formed integral with a plate 55 detachably secured to the side wall of the machine frame. Each drum has formed centrally therein a dust proof chamber 56 in which the bearing structure is housed.

The operating mechanism for the sets of friction clutches 29, 53, and 30, 51 will now be described. Interposed between the clutches 29, 53 and straddling the shaft 31 is a shipper yoke 57 pivoted at 58 on the machine frame. This shipper yoke is provided at opposite sides thereof with curved portions 59 engaging the pressure plates for the clutches respectively. Engaging the pressure plates for the friction clutches 30 and 51 is a similar shipper yoke 60 pivoted at 61 on the machine frame. The shipper yokes have integral projecting lever portions or arms 62 (see Fig. 7) bifurcated at their outer ends for connection to trunnions 63 and 64 respectively. Each of the trunnions is in the form of a nut threadedly connected to screws 65 and 66 respectively. The screw 65 is formed on a rotatable sleeve 67 rotatably supported within the side of the machine frame and carrying at its outer end a toothed clutch member 68. A similar rotatable sleeve 69 is secured to the screw 66 and is likewise journaled within the machine frame and carries a similar toothed clutch member 70. Extending axially through these sleeves is an operating rod 71 having keyed to its opposite ends toothed clutch members in the form of hand wheels 72, 73. A suitable plunger and groove connection 74 is employed for holding the rod 71 in its adjusted positions. It will thus be seen that when the hand wheel 72 is slid inwardly to connect the clutch teeth thereon with the clutch teeth on the member 68 and the hand wheel is rotated, the screw 67 is rotated and as a result the shipper yoke is swung about its pivot to apply one or the other of the friction clutches 29 and 53. When the rod 71 is slid in the opposite direction connecting the clutch teeth on the member 73 with the

clutch teeth on the member 70 and the rod is rotated, the screw 69 is rotated, swinging the shipper yoke 60 about its pivot to apply one or the other of the friction clutches 30 and 51. It will therefore be evident that the clutches of each set may be only alternatively applied and that the clutches may be controlled by the hand wheels 72, 73 from either side of the machine.

The mining machine is adapted to be mounted on a self-propelled truck during transport of the machine about the mine and mechanism is provided on the machine for driving the truck wheels. This truck driving mechanism includes a spur gear 75 meshing, as shown in Fig. 4, with the spur gear 44 of the slow speed gear train of the feeding mechanism. This spur gear 75 is fixed to a vertical shaft 76 suitably journaled within the machine frame and secured to the upper end of this shaft is a spur gear 77 projecting through an opening in the frame and adapted to mesh with a usual driving gear (not shown) carried on the truck. When the machine is mounted on the truck with the gear 77 in mesh with the truck driving gear, the truck wheels may be driven from the motor through the gearing 18, 19, 21, 22, 43, 44, 75, vertical shaft 76 and spur gear 77. Various modes 80 of operation of the improved machine will be clearly apparent to those skilled in the art and as the method of use of a room and pillar mining machine is well known, further description of the operation of the machine is 85 thought unnecessary.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine feeding mechanism including relatively rotatable feed operating and controlling members each adapted to cooperate directly with flexible feeding means, and a plural speed driving means for said members for rotating the latter either separately or simultaneously in a direction to draw in their respective flexible feeding means at relatively high speed or at relatively low speed, said means being operative to effect drive of one member at a low speed while the other member is simultaneously driven at a high speed and having embodied therein a slow speed driving mechanism including a final slow speed driving element, a fast speed driving mechanism including a final fast speed driving element, and friction controlling clutches for said mechanisms respectively, the final driving elements of 100

said mechanisms being common to the drive of both members.

2. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively low speed, said plural speed mechanism having embodied therein a slow speed gear train including a final slow speed driving element, a fast speed gear train including a final fast speed driving element, said final driving elements of said gear trains being common to the drive of both members, and friction controlling clutches individual to each member, one for slow speed and one for fast speed.

3. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively low speed, said plural speed mechanism having embodied therein a slow speed gear train including a final slow speed driving element through which both members are driven, a fast speed gear train including a final fast speed driving element through which both members are driven, and means for connecting either member in driving relation with the final driving element of either gear train at will, including friction clutches individual to each member, one for slow speed and one for fast speed.

4. A mining machine feeding mechanism comprising relatively rotatable feed operating and controlling members each adapted to cooperate directly with flexible feeding means, and a plural speed driving means for said members for rotating the latter either separately or simultaneously in a direction to draw in their respective flexible feeding means at relatively high speed or at relatively low speed including a slow speed driving mechanism including a final slow speed driving element, a fast speed driving mechanism including a final fast speed driving element, the final driving elements of both of said mechanisms being common to the drive of both members, and frictional controlling means, including a plurality of friction clutches associated with each mechanism for connecting either member to either mechanism at will.

5. A mining machine feeding mechanism comprising relatively rotatable feed operating and controlling members each adapted

to cooperate directly with flexible feeding means, and a plural speed driving means for said members for rotating the latter either separately or simultaneously in a direction to draw in their respective flexible feeding means at relatively high speed or at relatively low speed or to permit said members to rotate in a direction to pay out their respective flexible feeding means under various degrees of frictional resistance including a frictionally controlled slow speed driving mechanism including a final slow speed driving element and a frictionally controlled fast speed driving mechanism including a final fast speed driving element, the final driving elements of both of said mechanisms being common to the drive of both members and operative to effect drive of one member at a slow speed while the other member is simultaneously driven at a high speed.

6. A mining machine feeding mechanism comprising relatively rotatable feed operating and controlling members each adapted to cooperate directly with flexible feeding means, and a plural speed driving means for said members for rotating the latter either separately or simultaneously in a direction to draw in their respective flexible feeding means at relatively high speed or at relatively low speed or to permit said members to rotate in a direction to pay out their respective flexible feeding means under various degrees of frictional resistance including a frictionally controlled slow speed driving mechanism including a final slow speed driving element, a frictionally controlled fast speed driving mechanism including a final fast speed driving element, the final driving elements of both of said mechanisms being common to the drive of both members, and frictional means operable at will for connecting either member to either mechanism or for connecting one member to said slow speed mechanism while the other member is simultaneously connected to said fast speed mechanism.

7. A mining machine feeding mechanism comprising relatively rotatable feed operating and controlling members each adapted to cooperate directly with flexible feeding means, and a plural speed driving means for said members for rotating the latter either separately or simultaneously in a direction to draw in their respective flexible feeding means at relatively high speed or at relatively low speed, to permit said members to rotate in a direction to pay out their respective flexible feeding means under various degrees of frictional resistance or without such resistance including a frictionally controlled slow speed driving mechanism including a final slow speed driving element and a frictionally controlled fast speed driving mechanism including a final fast speed driving element, the final driving elements of both of said mechanisms being common to the drive of both

members and operative to effect drive of one member at a slow speed while the other member is simultaneously driven at a high speed.

8. A mining machine feeding mechanism comprising relatively rotatable feed operating and controlling members each adapted to cooperate directly with flexible feeding means, and a plural speed driving means for said members for rotating the latter either 5 separately or simultaneously in a direction to draw in their respective flexible feeding means at relatively high speed or at relatively low speed, to permit said members to rotate in a direction to pay out their respective flexible 10 feeding means under various degrees of frictional resistance or without such resistance including a frictionally controlled slow speed driving mechanism including a final slow speed driving element, a frictionally controlled fast speed driving mechanism including a final fast speed driving element, the final driving elements of both of said mechanisms being common to the drive of both members, and frictional means operable at will for connecting either member to either mechanism or for connecting one member to said slow speed mechanism while the other member is simultaneously connected to said fast speed mechanism. 15
- 20 9. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively low speed including a slow speed gear train having a final slow speed driving element, friction controlling clutches for connecting either member to the final driving element of said slow speed gear train, and a frictionally controlled fast speed gear train including a final fast speed driving element common to the drive of both members. 25
- 30 10. A mining machine feeding mechanism comprising relatively rotatable feed operating and controlling members each adapted to cooperate directly with flexible feeding means, and a plural speed driving mechanism for said members for rotating the latter in a direction to draw in their respective flexible feeding means either separately or simultaneously at relatively high speed or at relatively low speed or to permit said members to rotate in a direction to pay out their respective flexible feeding means under various degrees of frictional resistance including a frictionally controlled slow speed gear train including a final slow speed driving element, a frictionally controlled fast speed gear train including a final fast speed driving element, the final driving elements of both of said gear trains being common to the drive of both members, and friction controlling clutches operable at will for connecting either member to either gear train or for connecting one member to said slow speed gear train while the other member is simultaneously connected to said fast speed gear train. 35
- 40 11. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively low speed or to permit said members to rotate in a direction to pay out their respective flexible feeding means under various degrees of frictional resistance including a slow speed gear train having a final slow speed driving element, friction controlling clutches for connecting either member to the final driving element of said slow speed gear train, and a frictionally controlled fast speed gear train including a final fast speed driving element common to the drive of both members. 45
- 50 12. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively low speed, to permit said members to rotate in a direction to pay out their respective flexible feeding means under various degrees of frictional resistance, to rotate in a direction to pay out their respective flexible feeding means under various degrees of frictional resistance or without such resistance including a frictionally controlled slow speed gear train including a final slow speed driving element, a frictionally controlled fast speed gear train including a final fast speed driving element, the final driving elements of both of said gear trains being common to the drive of both members, and friction controlling clutches operable at will for connecting either member to either gear train or for connecting one member to said slow speed gear train while the other member is simultaneously connected to said fast speed gear train. 55
- 60 13. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means either separately or simultaneously at relatively high speed or at relatively low speed, to permit said members to rotate in a direction to pay out their respective flexible feeding means under various degrees of frictional resistance or without such resistance including a frictionally controlled slow speed gear train including a final slow speed driving element, a frictionally controlled fast speed gear train including a final fast speed driving element, the final driving elements of both of said gear trains being common to the drive of both members, and friction controlling clutches operable at will for connecting either member to either gear train or for connecting one member to said slow speed gear train while the other member is simultaneously connected to said fast speed gear train. 65

spective flexible feeding means under various degrees of frictional resistance or without such resistance including a slow speed gear train having a final slow speed driving element, friction controlling clutches for connecting either member to the final driving element of said slow speed gear train, and a frictionally controlled fast speed gear train including a final fast speed driving element common to the drive of both members.

14. A mining machine feeding mechanism comprising relatively rotatable feed operating and controlling members each adapted to cooperate directly with flexible feeding means, and a plural speed driving mechanism for said members including a slow speed gear train having a final slow speed driving element common to the drive of both members, a fast speed gear train having a final fast speed driving element common to the drive of both members, a controlling clutch for each member for connecting each member to the final driving element of said slow speed gear train, and a plurality of controlling clutches one for each member for connecting each member to the final driving element of said fast speed gear train.

15. A mining machine feeding mechanism comprising relatively rotatable feed operating and controlling members each adapted to cooperate directly with flexible feeding members, and a plural speed driving mechanism for said members including alined transmission elements one connected to each member, a slow speed gear train including a terminal gear coaxial with said transmission elements, clutches for connecting said transmission elements to said terminal gear, a fast speed gear train including a terminal gear coaxial with said transmission elements, and clutches for connecting said transmission elements in driving relation with said fast speed terminal gear.

16. A mining machine feeding mechanism comprising relatively rotatable feed operating and controlling members each adapted to cooperate directly with flexible feeding members, and a plural speed driving mechanism for said members including alined horizontal shafts one connected to each member, a slow speed gear train including a terminal gear coaxial with said shafts, clutches for connecting said shafts to said terminal gear, a fast speed gear train including a terminal gear coaxial with said shafts, and clutches for connecting said shafts in driving relation with said fast speed terminal gear.

17. A mining machine feeding mechanism comprising relatively rotatable feed operating and controlling members each adapted to cooperate directly with flexible feeding members, and a plural speed driving mechanism for said members including alined horizontal shafts extending transversely of the machine

one connected to each member, a slow speed gear train including a terminal gear coaxial with said shafts, clutches for connecting said shafts to said terminal gear, a fast speed gear train including a terminal gear coaxial with said shafts, and clutches for connecting said shafts in driving relation with said fast speed terminal gear.

18. A mining machine feeding mechanism comprising relatively rotatable feed operating and controlling members arranged with their axes parallel to a transverse vertical plane and each adapted to cooperate directly with flexible feeding means, and a plural speed driving mechanism for said members including fast and slow speed gearing including a terminal fast speed driving element and a terminal slow speed driving element, and means for connecting said members either separately or simultaneously in driving relation with the terminal driving elements of said gearing to effect independent drive of said members at either speed or simultaneous drive at different speeds.

19. A mining machine feeding mechanism comprising relatively rotatable feed operating and controlling members arranged with their axes parallel to a transverse vertical plane and each adapted to cooperate directly with flexible feeding means, and a plural speed driving means for said members including a fast and slow speed mechanism for driving said members at relatively high speed or at relatively low speed and including a terminal fast speed driving element and a terminal slow-speed driving element, and devices for connecting said members either separately or simultaneously to the terminal driving elements of said fast and slow speed mechanism, said means being operative to effect drive of one member at a slow speed while the other member is simultaneously driven at a high speed.

20. A mining machine feeding mechanism comprising relatively rotatable feed operating and controlling members arranged with their axes parallel to a transverse vertical plane and each adapted to cooperate directly with flexible feeding means, and a plural speed driving means for said members including a change speed mechanism common to the drive of both members, and means for connecting said members either separately or simultaneously in driving relation with said mechanism, said means being operative to effect drive of one member at one speed while the other member is simultaneously driven at a different speed.

21. A mining machine feeding mechanism including relatively rotatable feed operating and controlling members each adapted to cooperate directly with flexible feeding means, and motor operated devices for driving said members in a direction to draw in their respective flexible feeding means at relatively

high or relatively low speed including a horizontal transversely extending shaft, a fast speed gear train and a slow speed gear train, each gear train including a gear coaxial with said shaft, connections between one of said gears and said shaft, a clutch for connecting one of said members in driving relation with said latter gear, a clutch for connecting the other of said members in driving relation with said shaft, and separate driving connections between said other gear and said members.

22. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a horizontal transversely extending shaft, a fast speed gear train and a slow speed gear train, each gear train including a gear coaxial with said shaft, connections between one of said gears and said shaft, a clutch for connecting one of said members in driving relation with said latter gear, a clutch for connecting the other of said members in driving relation with said shaft, and separate driving connections between said other gear and said members including clutches one individual to each member.

23. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including alined shafts one connected to each member, a coaxial shaft, a fast speed gear train and a slow speed gear train, clutch devices for connecting said alined shafts in driving relation with one of said gear trains, and a separate clutch for connecting one of said members in driving relation with said coaxial shaft.

24. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a transversely extending horizontal shaft, fast and slow speed gear trains each including a terminal gear coaxial with said shaft, alined shafts coaxial with said shaft, clutch devices for connecting said alined shafts in driving relation with one of said terminal gears, and a connection between said coaxial shaft and said other terminal gear.

25. A mining machine feeding mechanism including relatively rotatable feed operating

and controlling members each adapted to cooperate directly with flexible feeding means, and motor operated devices for driving said members in a direction to draw in their respective flexible feeding means at relatively high or relatively low speed including a transversely extending horizontal shaft, fast and slow speed gear trains each including a terminal gear coaxial with said shaft, alined shafts coaxial with said shaft, clutch devices for connecting said alined shafts in driving relation with one of said terminal gears, a connection between said coaxial shaft and said other terminal gear, and clutch devices for connecting said last mentioned terminal gear in driving relation with said members respectively.

26. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed terminal gear elements, clutch devices for connecting said members in driving relation with one of said gear elements, a shaft coaxial with said elements and driven by said other gear element, a clutch for connecting one of said members to said latter gear element, and a clutch for connecting said other member to said coaxial shaft.

27. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed worm wheels, a shaft coaxial with said worm wheels, clutch devices for connecting said members in driving relation with one of said worm wheels, a clutch connecting said other worm wheel in driving relation with one of said members, and a clutch for connecting said other member in driving relation with said coaxial shaft.

28. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed worm wheels, a shaft coaxial with said worm wheels and driven directly by one

of the latter, clutch devices for connecting said members in driving relation with one of said worm wheels, a clutch connecting said other worm wheel in driving relation with one of said members, and a clutch for connecting said other member in driving relation with said coaxial shaft.

29. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed worm wheels and worms rotatable on parallel axes and meshing with said worm wheels respectively, a shaft coaxial with said worm wheels, clutch devices for connecting said members in driving relation with one of said worm wheels, a clutch connecting said other worm wheel in driving relation with one of said members, and a clutch for connecting said other member in driving relation with said coaxial shaft.

30. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed worm wheels and worms meshing with said worm wheels respectively, one of said worms rotating on a vertical axis, a shaft coaxial with said worm wheels and driven directly by one of the latter, clutch devices for connecting said members in driving relation with one of said worm wheels, a clutch connecting said other worm wheel in driving relation with one of said members, and a clutch for connecting said other member in driving relation with said coaxial shaft.

31. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed worm wheels and worms rotatable on parallel vertically extending axes and meshing with said worm wheels respectively, a shaft coaxial with said worm wheels and driven directly by one of the latter, clutch devices for connecting said members in driving relation with one of said worm wheels, a

clutch connecting said other worm wheel in driving relation with one of said members, and a clutch for connecting said other member in driving relation with said coaxial shaft.

32. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a bevel gear, a worm coaxial therewith, a fast speed gear train and a slow speed gear train, one of said gear trains including a worm wheel meshing with said worm and constituting a driving element for both members, and clutch devices for connecting either member in driving relation with either gear train.

33. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a bevel gear rotating about a vertical axis, a worm coaxial therewith, a fast speed gear train and a slow speed gear train, one of said gear trains including a worm wheel meshing with said worm and constituting a driving element for both members, and clutch devices for connecting either member in driving relation with either gear train.

34. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train, each gear train including a worm wheel and a worm meshing therewith, said worms being arranged on parallel vertical axes, and clutch devices for connecting either member in driving relation with either worm wheel or for connecting one member to one worm wheel and the other member simultaneously to the other worm wheel.

35. A mining machine feeding mechanism including relatively rotatable feed operating and controlling members each adapted to cooperate directly with flexible feeding means, and motor operated devices for driving said members in a direction to draw in their respective flexible feeding means at relatively high or relatively low speed including a fast speed gear train and a slow speed gear train each gear train including a worm wheel and a worm meshing therewith, said worm wheels being coaxially arranged and said worms being arranged on parallel vertical axes, and

clutch devices for connecting either member in driving relation with either worm wheel or for connecting one member to one worm wheel and the other member simultaneously to the other worm wheel.

36. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a bevel gear, a worm coaxial therewith and driven thereby, a worm rotating on a parallel axis, driving connections between said bevel gear and said last mentioned worm, worm wheels meshing with said worms respectively, and clutch devices for connecting either member in driving relation with either worm wheel.

37. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a bevel gear rotating on a vertical axis, a worm coaxial therewith and driven thereby, a worm rotating on a parallel axis, driving connections between said bevel gear and said last mentioned worm, worm wheels meshing with said worms respectively, and clutch devices for connecting either member in driving relation with either worm wheel.

38. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a motor driven gear, a worm coaxial therewith and driven thereby, a worm rotating on an axis parallel with said worm, driving connections between said last mentioned worm and said motor driven gear, worm wheels meshing with said worms respectively, and clutch devices for connecting either member in driving relation with either worm wheel or for connecting one member to one worm wheel and the other member simultaneously to the other worm wheel.

39. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a motor driven gear rotating about a vertical

axis, a worm coaxial therewith and driven thereby, a worm rotating on a parallel axis, driving connections between said last mentioned worm and said motor driven gear, worm wheels meshing with said worms respectively, and clutch devices for connecting either member in driving relation with either worm wheel or for connecting one member to one worm wheel and the other member simultaneously to the other worm wheel.

40. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed terminal elements, a shaft coaxial with said elements, one of said terminal elements being connected to one end of said shaft, connections between the opposite end of said shaft and one of said members, and driving connections between said other terminal element and both of said members, there being clutch devices for connecting either member in driving relation with either terminal element.

41. A mining machine feeding mechanism including relatively rotatable feed operating and controlling members each adapted to co-operate directly with flexible feeding means, and motor operated devices for driving said members in a direction to draw in their respective flexible feeding means at relatively high or relatively low speed including a fast speed gear train and a slow speed gear train, said gear trains including coaxial fast and slow speed terminal gears, a shaft coaxial with said gears and to which one of said gears is secured, a clutch for connecting one of said members in driving relation with said gear secured to said shaft, a clutch for connecting said other member in driving relation with said shaft and connected to the latter at the opposite end thereof, and clutch devices for connecting said members in driving relation with said other terminal gear. 100 105 110 115

42. A mining machine feeding mechanism including relatively rotatable feed operating and controlling members each adapted to co-operate directly with flexible feeding means, and motor operated devices for rotating said members either separately or simultaneously in a direction to draw in their respective flexible feeding means at relatively high speed or at relatively low speed including a fast speed gear train and a slow speed gear train, each gear train including a terminal gear element, clutch devices one individual to each member for connecting said members to said slow speed terminal gear element, and clutch devices one individual to each member.

for connecting either member in driving relation with said fast speed terminal gear element.

43. A mining machine feeding mechanism comprising relatively rotatable feed operating and controlling members arranged on axes parallel to a transverse vertical plane and each adapted to cooperate directly with flexible feeding means, and a plural speed driving means for said members for rotating the latter either separately or simultaneously in a direction to draw in their respective flexible feeding means at relatively high speed or at relatively low speed including a slow speed driving mechanism and a fast speed driving mechanism, said mechanisms being common to the drive of both members and operative to effect drive of one member at a slow speed while the other member is simultaneously driven at a high speed.

44. A mining machine feeding mechanism comprising relatively rotatable feed operating and controlling members arranged on axes parallel to a transverse vertical plane and each adapted to cooperate directly with flexible feeding means, and a plural speed driving mechanism for said members for rotating the latter either separately or simultaneously in a direction to draw in their respective flexible feeding means at relatively high speed or at relatively low speed including a slow speed gear train, a fast speed gear train, and means operable at will for connecting either member to either gear train or to connect one member to one gear train while the other member is simultaneously connected to the other gear train.

45. A mining machine feeding mechanism comprising relatively rotatable feed operating and controlling members arranged on axes parallel to a transverse vertical plane and each adapted to cooperate directly with flexible feeding means, and a plural speed driving means for said members for rotating the latter either separately or simultaneously in a direction to draw in their respective flexible feeding means at relatively high speed or relatively low speed including a slow speed driving mechanism, a fast speed driving mechanism, said mechanisms being common to the drive of both members, and frictional controlling means including a plurality of friction clutches associated with each mechanism for connecting either member to either mechanism at will.

46. A mining machine feeding mechanism comprising relatively rotatable feed operating and controlling members arranged on axes parallel to a transverse vertical plane and each adapted to cooperate directly with flexible feeding means, and a plural speed driving means for said members for rotating the latter either separately or simultaneously in a direction to draw in their respective flexible feeding means at relatively high speed

or at relatively low speed or to permit said members to rotate in a direction to pay out their respective flexible feeding means under various degrees of frictional resistance including a frictionally controlled slow speed driving mechanism, and a frictionally controlled fast speed driving mechanism, said mechanisms being common to the drive of both members and operative to effect drive of one member at a slow speed while the other member is simultaneously driven at a fast speed.

47. A mining machine feeding mechanism comprising relatively rotatable feed operating and controlling members arranged on axes parallel to a transverse vertical plane and each adapted to cooperate directly with flexible feeding means, and a plural speed driving means for said members for rotating the latter either separately or simultaneously in a direction to draw in their respective flexible feeding means at relatively high speed or at relatively low speed or to permit said members to rotate in a direction to pay out their respective flexible feeding means under various degrees of frictional resistance including a frictionally controlled slow speed driving mechanism, a frictionally controlled fast speed driving mechanism, said mechanisms being common to the drive of both members, and frictional means operable at will for connecting either member to either mechanism or for connecting one member to one mechanism while the other member is simultaneously connected to the other mechanism.

48. A mining machine feeding mechanism comprising relatively rotatable feed operating and controlling members arranged on axes parallel to a transverse vertical plane and each adapted to cooperate directly with flexible feeding means, and a plural speed driving mechanism for said members for rotating the latter in a direction to draw in their respective flexible feeding means either separately or simultaneously at relatively high speed or at relatively low speed or to permit said members to rotate in a direction to pay out their respective flexible feeding means under various degrees of frictional resistance including a frictionally controlled slow speed gear train, a frictionally controlled fast speed gear train, said gear trains being common to the drive of both members, and friction controlling clutches operable at will for connecting either member to either gear train or for connecting one member to one gear train while the other member is simultaneously connected to the other gear train.

49. A mining machine feeding mechanism comprising relatively rotatable feed operating and controlling members arranged on axes parallel to a transverse vertical plane and each adapted to cooperate directly with flexible feeding means, and a plural speed

driving mechanism for said members for rotating the latter either separately or simultaneously in a direction to draw in their respective flexible feeding means at relatively 5 high speed or at relatively low speed including a slow speed gear train, friction controlling clutches, one for connecting each member to said slow speed gear train, and a frictionally controlled fast speed gear train common to the drive of both members.

50. A mining machine feeding mechanism comprising relatively rotatable feed operating and controlling members arranged on axes parallel to a transverse vertical plane 15 and each adapted to cooperate directly with flexible feeding means, and a plural speed driving mechanism for said members for rotating the latter either separately or simultaneously in a direction to draw in their respective flexible feeding means at relatively high speed or at relatively slow speed or to permit said members to rotate in a direction to pay out their respective flexible feeding means under various degrees of frictional resistance including a slow speed gear train, friction controlling clutches, one for connecting each member to said slow speed gear train, and a frictionally controlled fast speed gear train common to the drive of both members.

51. A mining machine feeding mechanism comprising relatively rotatable feed operating and controlling members arranged on axes parallel to a transverse vertical plane 35 and each adapted to cooperate directly with flexible feeding means, and a plural speed driving mechanism for said members including a slow speed gear train common to the drive of both members, a fast speed gear train common to the drive of both members, a controlling clutch for each member for connecting each member to said slow speed gear train, and a plurality of controlling clutches one for each member for connecting each member to said fast speed gear train.

52. A mining machine feeding mechanism comprising relatively rotatable feed operating and controlling members each adapted to cooperate directly with flexible feeding 50 means, and a plural speed driving means for said members for rotating the latter either separately or simultaneously in a direction to draw in their respective flexible feeding means at relatively high speed or at relatively low speed including a slow speed driving mechanism, a fast speed driving mechanism, said mechanisms including coaxial terminal elements common to the drive of both members, and frictional controlling means including a plurality of friction clutches associated with each mechanism for connecting either member to either mechanism at will.

53. A mining machine feeding mechanism comprising relatively rotatable feed operat-

ing and controlling members each adapted to cooperate directly with flexible feeding means, and a plural speed driving means for said members for rotating the latter either separately or simultaneously in a direction to draw in their respective flexible feeding means at relatively high speed or at relatively low speed or to permit said members to rotate in a direction to pay out their respective flexible feeding means under various degrees of frictional resistance, said means being operative to effect drive of one member at one speed and the other member simultaneously at the other speed and including a frictionally controlled slow speed driving mechanism 70 and a frictionally controlled fast speed driving mechanism, said mechanisms including coaxial terminal elements common to the drive of both members.

54. A mining machine feeding mechanism comprising relatively rotatable feed operating and controlling members each adapted to cooperate directly with flexible feeding means, and a plural speed driving means for said members for rotating the latter either 80 separately or simultaneously in a direction to draw in their respective flexible feeding means at relatively high speed or at relatively low speed or to permit said members to rotate in a direction to pay out their respective flexible feeding means under various degrees of frictional resistance, said means being operative to effect drive of one member at one speed and the other member simultaneously at the other speed and including a frictionally controlled slow speed driving mechanism, a frictionally controlled fast speed driving mechanism, said mechanisms including coaxial terminal elements common to the drive of both members, and frictional 90 means for connecting either member to either mechanism at will.

55. A mining machine feeding mechanism comprising relatively rotatable feed operating and controlling members each adapted to cooperate directly with flexible feeding means, and a plural speed driving mechanism for said members for rotating the latter in a direction to draw in their respective flexible feeding means either separately or simultaneously at relatively high speed or at relatively low speed or to permit said members to rotate in a direction to pay out their respective flexible feeding means under various degrees of frictional resistance, said 110 mechanism being operative to effect drive of one member at one speed and the other member simultaneously at the other speed and including a frictionally controlled slow speed gear train, a frictionally controlled fast speed 115 gear train, said gear trains including coaxial terminal elements common to the drive of both members, and friction controlling clutches operable at will for connecting either member to either gear train.

56. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively 10 low speed including a slow speed gear train, friction controlling clutches for connecting either member to said slow speed gear train, and a frictionally controlled fast speed gear train common to the drive of both members, 15 said gear trains including coaxial final driving elements.

57. A mining machine feeding mechanism comprising relatively rotatable feed operating and controlling members each adapted to cooperate directly with flexible feeding means, and a plural speed driving mechanism for said members for rotating the latter either separately or simultaneously in a direction to draw in their respective flexible feeding means at relatively high speed or at relatively 20 low speed including a slow speed gear train, friction controlling clutches for connecting either member to said slow speed gear train, and a frictionally controlled fast speed gear train common to the drive of both members, 25 said gear trains including coaxial final driving elements.

58. A mining machine feeding mechanism comprising relatively rotatable feed operating and controlling members each adapted to cooperate directly with flexible feeding means, and a plural speed driving mechanism for said members including a slow speed gear train common to the drive of both members, a fast speed gear train common to the drive of both members, said gear trains including 30 final driving elements arranged in coaxial relation, a controlling clutch for each member for connecting each member to said slow speed gear train, and a plurality of controlling clutches one for each member for connecting each member to said fast speed gear train.

59. A mining machine feeding mechanism comprising relatively rotatable feed operating and controlling members arranged with their axes parallel to a transverse vertical plane and each adapted to cooperate directly with flexible feeding means, said members being of the same size and diameter and rotatable at the same peripheral speeds and either capable of acting as a feed member 35 and a controlling member, and a plural speed driving mechanism for said members including a fast and slow speed gearing common to the drive of both mechanisms, and means for connecting said members either separately or simultaneously in driving relation with

said gearing to effect independent drive of said members at either speed.

60. A mining machine feeding mechanism comprising relatively rotatable feed operating and controlling members arranged with their axes parallel to a transverse vertical plane and each adapted to cooperate directly with flexible feeding means, said members being of the same size and diameter and rotatable at the same peripheral speeds and either capable of acting as a feed member and a control member, and a plural speed driving means for said members, including a fast and slow speed mechanism common to the drive of both members for driving said members at relatively high speed or at relatively 70 low speed, and devices for connecting said members either separately or simultaneously to said fast and slow speed mechanism, said means being operative to effect driving 75 of one member at a slow speed while the other member is simultaneously driven at a high speed.

61. A mining machine feeding mechanism including relatively rotatable feed operating and controlling members each adapted to cooperate directly with flexible feeding means, and motor operated devices for driving said members in a direction to draw in their respective flexible feeding means at 80 either a relatively high or a relatively low speed including a fast speed gear train and a slow speed gear train, said gear trains having terminal driving elements rotating on aligned axes, and means for connecting said members in driving relation with either terminal element providing for the connection of both members to either element simultaneously or for the connection of one member to one element and simultaneous connection of the other member to the other element, said fast speed terminal element always being disconnected from said members during driving of said members by said slow speed 85 terminal element.

62. A mining machine feeding mechanism including relatively rotatable feed operating and controlling members each adapted to cooperate directly with flexible feeding means, and motor operated devices for driving said members in a direction to draw in their respective flexible feeding means at either a relatively high or a relatively low speed including a fast speed gear train and a slow speed gear train, said gear trains having terminal driving elements rotating on aligned axes, and means for connecting said members in driving relation with either terminal element including a fast speed controlling clutch and a slow speed controlling clutch 115 individual to each member, said fast speed terminal element always being disconnected from said members during driving of said members by said slow speed terminal element.

63. A mining machine feeding mechanism including relatively rotatable feeding members each adapted to cooperate directly with flexible feeding means, and motor operated driving means therefor including a slow speed gear train and a high speed gear train each including a terminal gear and clutches for connecting either member to either gear or for connecting one member to one terminal gear while the other member is simultaneously connected to the other terminal gear. 10
64. A mining machine feeding mechanism including relatively rotatable feeding members each adapted to cooperate directly with flexible feeding means, and motor operated driving means therefor including a slow speed gear train and a high speed gear train each including a terminal gear and clutches for connecting either member to either gear 15
- 20 and means for operating said clutches to effect driving of one member at one speed and the other simultaneously at the other speed or vice versa.
65. A mining machine feeding mechanism including relatively rotatable feeding members each adapted to cooperate directly with flexible feeding means, and motor operated driving means therefor for rotating said members either separately or simultaneously 25
- 30 in a direction to draw in their respective flexible feeding means at relatively high speed or at relatively low speed including a fast speed gear train and a slow speed gear train each having a terminal gear and clutches for connecting either member in driving relation with either terminal gear or for connecting one member to one terminal gear while the other member is simultaneously connected to the other terminal gear. 35
- 40 66. A mining machine feeding mechanism including relatively rotatable feeding members each adapted to cooperate directly with flexible feeding means, and motor operated driving means for said members for effecting drive thereof either separately or simultaneously including a fast speed gear train and a slow speed gear train each having a terminal gear, the terminal gears of said trains being coaxially arranged, and clutch 45
- 50 mechanism for each gear for connecting either member in driving relation therewith or for connecting one member to one terminal gear while the other member is simultaneously connected to the other terminal gear. 55
- 60 67. A mining machine feeding mechanism including relatively rotatable feeding members each adapted to cooperate directly with flexible feeding means, and motor operated driving means therefor including a fast speed mechanism and a slow speed mechanism having final fast and slow speed driving elements through which either member may be driven, and clutch mechanism for connecting either member in driving relation with the final 65
- driving element of either mechanism or for connecting one member to one driving element while the other member is simultaneously connected to the other driving element. 70
68. A mining machine feeding mechanism including relatively rotatable feeding members each adapted to cooperate directly with flexible feeding means, and motor operated driving means for effecting rotation thereof either separately or simultaneously including a fast speed gear train and a slow speed gear 75
- train having final fast and slow speed driving elements through which either member may be driven, and clutch mechanism for connecting either member in driving relation with the final driving element of either gear train or for connecting one member to one driving element while the other member is simultaneously connected to the other driving element. 80
69. A mining machine feeding mechanism including relatively rotatable feeding members each adapted to cooperate directly with flexible feeding means, and motor operated driving means therefor for effecting rotation thereof either separately or simultaneously 85
- 90 in a direction to draw in their respective flexible feeding means including a fast speed gear train and a slow speed gear train having fast and slow speed driving elements through which either member may be driven, and clutch mechanism for connecting either member in driving relation with the final driving element of either gear train or for connecting one member to one driving element while the other member is simultaneously connected to the other driving element. 95
70. A mining machine feeding mechanism including relatively rotatable feeding members each adapted to cooperate directly with flexible feeding means, and motor operated driving means for said members including a fast speed gear train and a slow speed gear train, said gear trains including coaxial fast and slow speed worm wheels, and clutch means for connecting either member to one worm wheel or to the other or for connecting one member to one worm wheel while the other member is simultaneously connected to the other worm wheel. 105
71. A mining machine feeding mechanism including relatively rotatable feeding members each adapted to cooperate directly with flexible feeding means, and motor operated driving means for said members including a fast speed gear train and a slow speed gear train, said gear trains including coaxial fast and slow speed worm wheels, and clutch means for connecting either member to one worm wheel or to the other, one worm wheel being operable to effect rotation of said members either separately or simultaneously at relatively low speed, the other worm wheel being operable to drive said members separately or simultaneously at relatively high speed and both being operable to effect rotation of one 110
- 115
- 120
- 125
- 130

member at one speed and the other member simultaneously at the other speed.

72. A mining machine feeding mechanism including relatively rotatable feeding members each adapted to cooperate directly with flexible feeding means, and motor operated driving means for said members including a fast speed gear train and a slow speed gear train, said gear trains each including a final driving element and clutch mechanism operable to effect drive of either member through the final driving element of one gear train or through the final driving element of the other or to effect drive of one member through the final driving element of one gear train while driving of the other member is simultaneously effected through the final driving element of the other gear train.

73. A mining machine feeding mechanism including relatively rotatable feeding members each adapted to cooperate directly with flexible feeding means, and motor operated driving means for said members including a fast speed gear train and a slow speed gear train, said gear trains including final driving elements and clutch mechanism operable to effect drive of either member through one gear train or through the other or to effect drive of one member through the final driving element of one gear train while driving of the other member is simultaneously effected through the final driving element of the other gear train, said clutch mechanism including friction controlling clutches operable to connect either member in driving relation with the final driving element of either gear train.

74. A mining machine feeding mechanism including relatively rotatable feeding members each adapted to cooperate with flexible feeding means, and motor operated driving means for said members including fast and slow speed worm gearing, said gearing including a final fast speed worm wheel and a final slow speed worm wheel, and clutch mechanism for connecting either member to the final worm wheel of either gearing or for connecting one member to one worm wheel while the other member is simultaneously connected to the other worm wheel.

75. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear, and friction clutches individual to each member for respectively connecting either terminal gear in driving relation to that member.

76. A mining machine feeding mechanism including relatively rotatable feeding mem-

bers each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear and said gears being coaxially arranged, and friction clutches individual to each member for respectively connecting either terminal gear in driving relation to that member.

77. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear rotating on a horizontal axis, and friction clutches individual to each member for respectively connecting either terminal gear in driving relation to that member.

78. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear rotating on a horizontal transversely extending axis, and friction clutches individual to each member for respectively connecting either terminal gear in driving relation to that member.

79. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each gear train including a worm wheel, and friction clutches one individual to each member for connecting either worm wheel in driving relation with either member or for connecting one member to one worm wheel while the other member is simultaneously connected to the other worm wheel.

80. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a

fast speed gear train and a slow speed gear train, said gear trains each including a final driving element common to the drive of both of said members, and clutch mechanism operable to effect drive of one of said members at relatively high speed while said other member is driven at relatively low speed and vice versa.

81. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, said gear trains each including a final driving element common to the drive of both of said members, and clutch mechanism operable to effect drive of one of said members at relatively high speed while said other member is driven at relatively low speed and vice versa and controllable to permit rotation of said members in a direction to pay out their respective flexible feeding means under various degrees of frictional resistance.

82. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, said gear trains each including a final driving element common to the drive of both of said members, and clutch members operable to effect drive of one of said members at relatively high speed while said other member is driven at relatively low speed and vice versa and controllable to permit rotation of said members in a direction to pay out their respective flexible feeding means under various degrees of frictional resistance or without such resistance.

83. A mining machine feeding mechanism including relatively rotatable feeding members each adapted to cooperate directly with flexible feeding means, and motor operated devices for rotating said members either separately or simultaneously in a direction to draw in their respective flexible feeding means including a fast speed gear train and a slow speed gear train, each gear train including a terminal gear and said gears being coaxially arranged, and clutch devices for connecting either member in driving relation with either terminal gear or for connecting one member with one terminal gear while the other member is simultaneously connected to the other terminal gear.

84. A mining machine feeding mechanism including relatively rotatable feeding mem-

bers each adapted to cooperate with flexible feeding means, and motor operated driving means for said members including fast and slow speed worm gearing common to the drive of both feeding members, said gearing including coaxial fast and slow speed worm wheels, and clutch mechanism for connecting either member in driving relation with the worm wheel of either gearing or for connecting one member to one worm wheel while the other member is simultaneously connected to the other worm wheel.

85. In a mining machine, a machine frame, a motor, feeding mechanism driven by said motor including relatively rotatable feed drums arranged at opposite sides of said frame and each adapted to cooperate with a feed cable, and a plural speed driving mechanism for said drums for rotating the latter either separately or simultaneously in a direction to wind in their respective feed cables at relatively low speed and at relatively high speed, said driving mechanism including a high speed drive and a slow speed drive, said drives being common to both drums and fast and slow speed frictional controlling clutches individual to each drum.

86. In a mining machine, a machine frame, a motor, feeding mechanism driven by said motor including relatively rotatable feed drums arranged on horizontal axes at opposite sides of said frame and each adapted to cooperate with a feed cable, and a plural speed driving mechanism for said drums for rotating the latter either separately or simultaneously in a direction to wind in their respective feed cables at relatively low speed and at relatively high speed, said driving mechanism including a high speed drive and a slow speed drive, said drives being common to both drums and fast and slow speed frictional controlling clutches individual to each drum.

87. In a mining machine, a machine frame, a motor, feeding mechanism driven by said motor including relatively rotatable feed drums arranged on horizontal axes extending transversely of the machine at opposite sides of said frame and each adapted to cooperate with a feed cable, and a plural speed driving mechanism for said drums for rotating the latter either separately or simultaneously in a direction to wind in their respective feed cables at relatively low speed and at relatively high speed, said driving mechanism including a high speed drive and a slow speed drive, said drives being common to both drums and fast and slow speed frictional controlling clutches individual to each drum.

In testimony whereof I affix my signature.
MORRIS P. HOLMES.
